(57) **CLAIM**

The ornamental design for a weighted wheel, as shown and described.

DESCRIPTION

FIG. 1 is a front view of a weighted wheel.

FIG. 2 is a top view of the weighted wheel of FIG. 1.

FIG. 3 is a side view of the weighted wheel of FIG. 1; and, FIG. 4 is a front perspective view of the weighted wheel of FIG. 1.

The broken lines depict boundaries of the claimed design. Portions of the weighted wheel not shown in the Figures, including any portion of the rear of the weighted wheel not shown in the Figures, form no part of the claimed design.

1 Claim, 4 Drawing Sheets
